A. H. LEE,
APPARATUS FOR COVERING PRINTING ROLLS,
APPLICATION FILED JULY 15, 1918.

1,355,481.

Patented Oct. 12, 1920.

UNITED STATES PATENT OFFICE.

ALBERT H. LEE, OF NEW YORK, N. Y., ASSIGNOR TO THE FUCHS & LANG MANUFACTURING COMPANY, OF NEW YORK, N. Y., A CORPORATION OF NEW YORK.

APPARATUS FOR COVERING PRINTING-ROLLS.

1,355,481.

Specification of Letters Patent. Patented Oct. 12, 1920.

Application filed July 15, 1918. Serial No. 245,052.

To all whom it may concern:

Be it known that I, ALBERT H. LEE, a citizen of the United States, residing in the borough of Bronx, county of Bronx, city and State of New York, have invented certain new and useful Improvements in Apparatus for Covering Printing-Rolls, of which the following is a specification.

My invention relates to an apparatus for drawing leather covers or skins over lithographic printing rolls and tightening or stretching the same thereon, and it more particularly relates to a means for applying and tightening the outer or leather covers of such rolls.

In practice lithographic rolls are usually surrounded by flannel and felt covers and then by tight fitting seamless leather covers. Heretofore these outer covers were usually drawn on the rolls by hand. The hand operation being uneven and jerky produces creases and wrinkles both in the leather cover and in the nether fabric coverings of the rolls. Before the rolls could be used it was necessary to remove these creases and wrinkles so as to have an absolutely smooth surface for printing. The method of putting on the covers by hand is exceedingly difficult and tedious and requires the services of three or four men to make the cover sufficiently tight, whereas with my invention one man can do the work very easily. It is an object of my invention to produce a means and method for drawing these covers over the lithographic rolls smoothly and quickly and so that no unevenesses are caused in the nether coverings of the roll or in the leather cover itself.

My invention is also adapted to take up the slack or stretch that occurs in these leather covers after they have been in use on the rolls for some time, as will be herein-after described.

My invention includes means for circumferentially gripping the outer or leather cover and drawing it over the roll. Other features of my invention and objects and advantages thereof will appear from the following particular description of means embodying my invention.

I shall now describe the apparatus illustrated in the accompanying drawings and

embodying my invention, and shall thereafter point out my invention in claims.

Figure 1 is a vertical sectional elevation of the apparatus showing it in the act of drawing the cover on the roll.

Fig. 2 is an enlarged sectional elevation of the clamping or gripping means for holding the cover in the drawing operation showing this gripping means in locked or closed position.

Fig. 3 is a plan view of this clamping or gripping means.

Fig. 4 is a cross section of the same taken on the line X—X of Fig. 3.

Fig. 5 is a sectional elevation of the outer or pivotal ring of the clamping means.

Figs. 6 and 7 are detail sectional elevations of the outer and inner clamping rings, respectively, of the clamping or gripping means.

Fig. 8 is an elevation of a lithographic roll having the outer or leather cover in position and ready to be put into use.

The apparatus for drawing covers over rolls illustrated in the drawings and embodying my invention consists of clamping or gripping means having an outer pivotal ring member 1 and clamping or gripping rings 2 and 3. The inner wall 4 of the clamping ring 3 is made straight and of a diameter slightly greater than that of the lithographic roll on which it is to be used. The outer wall 5 of the ring 3 is of conical form and is provided with a flange 6 at the bottom thereof. The clamping ring 2 has a straight outer wall 7 and a conical inner wall 8. This conical inner wall 8 is adapted to fit over the conical outer wall 5 of the clamping ring 3. The outer wall 7 is provided with two abutments 9 directly opposite each other, and forming bearing faces for the clamping rings. The ring 1 has an inner wall 11 provided with two inwardly extending abutments 10 directly opposite each other which align with the abutments or bearing faces 9 on the outer wall 7 of the ring 2. The ring 1 fits over and is adapted to pivot or turn on the ring 2. It is held in place by screw threaded pivot bolts 12 passing through the ring 1 and the abutments 9 and 10 and into the ring 2. The ring 1 is provided with two elongated pro-

100

jections placed at right angles to the bearing faces of the abutments 9 and 10, one forming a handle 13 and the other forming the fulcrum end 14 of a lever formed by 5 the ring 1 and these projections 13 and 14. An extension 15 is provided for the handle 13 consisting of a piece of pipe or other suitable material. A toothed rack 16 placed against a wall or other suitable support is 10 provided to be used in conjunction with the clamping member as hereinafter described.

In using my invention the operator takes the usual outer or leather cover 17 having one end 18 sewed up and the other end 19 15 open, and draws the open end 19 through the ring 2. The ring 3 is then placed in the open end 19 and forced into the ring 2, thus locking the end 19 of the leather cover between these two rings. The leather cover 20 17 having been secured, the clamping means are placed over the lithographic roll 20 having its nether coverings thereon as indicated by the dotted lines at its outer edges. The inner wall 4 of the clamping ring 3 fits 25 smoothly and snugly over the roll 20. The roll 20 has projecting shafts 21 at each end. The uncovered shaft 21 is placed in a socket 22 secured to the floor.

The projecting fulcrum-end 14 of the 30 ring 1 is now placed in one of the upper notches of the rack 16 that is lower than the pivot-bolt 12, and the handle 15 is moved downward. The ring 1 will pivot about the clamping rings 2 and 3 holding the 35 leather cover 17, and the downward movement on the handle 15 will draw the entire apparatus and cover 17 down on the roll 20 to or slightly below the notch in the rack 16 in which the lever end 14 is placed. 40 This lever end 14 is then removed and placed in a lower notch and the operation repeated again and again until the cover 17 is completely drawn over the roll 20. The 45 end 19 of the cover 17 is then released from the clamping rings and sewed up as shown in Fig. 8 and the roll is ready for use. The 50 complete gripping of the entire end of the leather cover and the even downward movement of the clamping means over the roll 20 results in an avoidance of wrinkles and creases both in the cover 17 and in the nether coverings of the roll 20.

In practice after the roll has been in use 55 for some time, this outer leather cover usually stretches and it is necessary to take up the looseness or slack. Heretofore this had to be done by hand with the same resultant effects that were had in originally drawing on the cover. With my invention, the 60 strings or threads are withdrawn from the end of the cover and the end is gripped between the rings 2 and 3 and the handle 15 is depressed in the same manner as used in the original operation. The looseness is 65 thus quickly and readily taken up and the

end is resewn or tied and the roll is ready for use again.

In using my invention it is not always necessary to use the rack 16 though this is preferable in covering large rolls. The 70 clamping and drawing means may be drawn down by hand in the case of small rolls.

It is obvious that various modifications may be made in the construction shown in the drawings and above particularly described within the principle and scope of 75 my invention.

I claim:

1. An apparatus for drawing covers over printing rolls comprising means for gripping one end of the cover consisting of clamping rings adapted to fit around the roll, and means secured to such clamping rings for drawing the gripping means longitudinally of the rolls. 80

2. An apparatus for drawing covers over printing rolls comprising clamping rings for gripping one end of the cover and a member pivoted to such clamping rings for forcing such clamping rings over the roll. 90

3. An apparatus for drawing covers over printing rolls comprising a ring member adapted to fit over the roll and forming an inner clamping member, an outer clamping member adapted to coöperate with the inner 95 clamping member to hold the cover between them, and a member pivoted to the outer clamping member to draw the cover over the roll. 95

4. An apparatus for drawing covers over 100 printing rolls comprising an inner circular member fitting over the roll, a middle circular member fitting over the inner member, these two members forming clamping means for gripping the end of the cover, 105 and a circular member surrounding the middle circular member and pivoted thereto for drawing the cover over the roll.

5. An apparatus for drawing covers over printing rolls comprising an inner circular 110 member fitting over the roll, a middle circular member fitting over the inner member, these two members forming clamping means for gripping the end of the cover, and a circular member surrounding the 115 middle circular member and pivoted thereto, the pivoted circular member having a handle at one side and a projecting member at the opposite side.

6. An apparatus for drawing covers over 120 printing rolls comprising an inner circular member fitting over the roll, a middle circular member fitting over the inner member, these two members forming clamping means for gripping the end of the cover, 125 a circular member surrounding the middle circular member and pivoted thereto, the pivoted circular member having a handle at one side and a projecting member at the opposite side, and a toothed rack adapted to 130

engage the projecting member of the pivoted circular member when the apparatus is being used.

7. An apparatus for drawing covers over printing rolls comprising means for gripping one end of the cover and adapted to fit around the roll, a lever operatively con-

nected to the gripping means, and a fulcrum for the lever, whereby the power of the lever may be applied to draw the cover 10 over the roll.

In testimony whereof I have affixed my signature to this specification.

ALBERT H. LEE.
